MAURICE F. GEER, OF ROCHESTER, NEW YORK, ASSIGNOR TO GENERAL RAILWAY SIGNAL COMPANY, OF GATES, NEW YORK, A CORPORATION OF NEW YORK.

TIME-ANNOUNCING SYSTEM.

1,121,828.

Specification of Letters Patent.

Patented Dec. 22, 1914.

Application filed March 1, 1912. Serial No. 680,860.

To all whom it may concern:

Be it known that I, MAURICE F. GEER, a citizen of the United States, and resident of the city of Rochester, in the county of Monroe and State of New York, have invented a new and useful Time-Announcing System, of which the following is a specification.

This invention relates to a time announcing system, and particularly to a system of announcing time applicable to a selective signaling system.

The primary object of this invention is to construct and arrange a system of circuits and devices whereby time may be announced at all of the stations comprised in a selective signaling system, by employing just as much of the selective signaling apparatus as is possible, and without interfering in any manner with the normal selective operation of the system.

For a great many years the movements of trains upon railways have been facilitated by the use of the telegraph. The ordinary method is to have a so called despatcher at a central point, who transmits orders by telegraph to local stations concerning the desired movements of trains. At present the telegraph is being rapidly superseded by the telephone for such device.

When the telegraph is used for governing train movements, it is a very simple matter to announce time to all of the local stations, and at present it is done by forbidding all use of the lines from about two minutes before eleven o'clock in the morning to about two minutes after eleven o'clock. During such time the telegraph wire is connected to the so called "Western Union time circuit", which causes well understood ticks by all the telegraph instruments on the line to which it is connected, so that each local operator may adjust his clock daily.

When the telephone is used for controlling train movements, it is necessary to also have a system for selectively calling the local stations, but heretofore it has seemed impossible to announce time by such selective signaling systems, but as heretofore pointed out it is one of the objects of applicant's invention to accomplish such act.

In the drawings accompanying this specification in which like characters of reference refer to like parts, and in which one embodiment of applicant's idea of means is

shown, Figure 1 is a diagrammatic view of apparatus and circuits used in applicant's invention located at the despatcher's station; Fig. 2 is a continuation of Fig. 1 and shows diagrammatically the construction and arrangements of parts at a local station; Fig. 3 is a continuation of Fig. 2 showing the construction and arrangement at another local station.

The selector and time announcing system shown in the drawings accompanying this specification consists generally of a despatcher's station A, and local stations as B and C.

1 and 2 designate line wires extending from the despatcher's station A, to the local B and C. At the despatcher's station are located calling keys, individual to each local station, which, when manually operated, cause, in the embodiment shown, a bell to be rung at the particular local station with which the despatcher desires to communicate. The individual keys are constructed, arranged and connected as fully set forth in the co-pending joint application of Maurice F. Greer and Richard C. Leake, Serial No. 626,285, filed May 10th, 1911.

In the drawings, Fig. 1, numerals 3 and 4 designate two toothed wheels which are mounted upon a common shaft together with wheel 82, and comprise together with sector 5 the essential parts of the individual key adapted for causing the selector at the station B to operate, and so cause the indicating device to operate at that station.

6 and 7 designate toothed wheels, mounted on a common shaft upon which wheel 89 is mounted and together with sector 8 comprise the essential parts of the individual key for causing the selector at station C to operate and so cause the indicator at that station to operate.

9 and 10 designate toothed wheels mounted on a common shaft, which are similar to wheels 3 and 4 and 6 and 7 but unlike wheels 3 and 4 and 6 and 7 are not associated with sectors such as 5 and 8 and wheels such as 82 and 89.

Each of the wheels when rotated, engages with a fixed brush such as 11, 12, 13, 14, 15, 16, 83 and 163 and the sectors 5 and 8 when rotated, engage with the brushes 17 and 18 respectively. With this difference, however, that upon the initial operation of an individual key, the sectors such as 5 and 8 are immediately moved into contact with the

springs such as 17 and 18 and remain in contact with said springs until the parts of the key all return automatically to their initial position as fully set forth in the application hereinbefore mentioned, as the sectors 5 and 8 are moved in the direction of the arrows *a*, upon an initial operation of the key, and move in a direction opposite to the arrow *a*, when the parts of the key return to its initial position. The toothed wheels 3, 4, 6, 7, 9, 10, 82 and 89 are not moved by the initial operation of the key, but remain stationary while the key is being operated manually, but as soon as the key starts to return to the initial position automatically, they rotate in the direction of the arrows *b* until they have made one complete revolution from the initial position as fully set forth in the application hereinbefore mentioned. During the movement, the teeth and projections upon the wheels successively move into contact with the springs 11, 12, 13, 14, 15, 16, 83 and 163, so that the path of an electric circuit through the wheel is intermittently completed and broken.

19 designates the movable member of an ordinary push key; 20, designates a source of electric current; 21 designates the motor end of a motor generator, the generator being designated by 22; 23 designates a relay having an armature 25 to which an arm 26 is connected, which causes a connection to be made from wire 27 to wire 28 when the relay coils are energized.

29 designates a switch so connected as to complete and break the circuit between points 30 and 31 and 32 and 33 when moved in one direction; 34 designates a line control relay which has two separate coils 35 and 36, and a pivoted armature 37 so arranged that the passage of current through one coil as 35, causes the left hand end of the armature to be drawn upwardly and by the passage of current through the coil 36, the right hand end of the armature to be drawn upwardly thereby causing the arm 38 attached thereto, to move the members 39 and 40 into contact with either points 41 and 42 or 43 and 44.

50 The initial operation of the individual key for calling station B, causes sector 5 to contact with spring 17 so that a circuit is completed in which current flows as follows: positive side of battery 20, wires 45, 46, 47, 48, 49, 50, 51, 84, 52, and 53, sector 5, spring 17, wires 54, 55, point 33, wire 56, relay 23, wires 57, 58 and 59 to the negative terminal of the battery. The current flowing in the above traced path, causes the relay 23 to be energized thereby actuating armature 25 and arm 26 so as to connect wires 27 and 28 so that current then flows from the source 20 in the following path to cause the motor 21 to operate: positive terminal of battery 20, wires 45, 60 and 28, arm 26, wire 27, motor

21, and wires 61 and 59 to the negative terminal of the battery. Rotation of the armature of motor 21 causes a rotation of the armature of generator 22 and so causes a generation of electrical current which may be conveyed by means of wire 62 which is connected to points 42 and 44, and by means of wire 65 which is connected to points 41 and 43.

The initial manual movement of the sector 5 causes the almost instant actuation of motor 21 and the rotation of the armature of generator 22, so that by the time the manual means for operating the key are withdrawn, and the automatic means to return the key to initial operation begins to act thereby causing a rotation of wheels 3 and 4, the generator 22 has acquired sufficient speed to cause a flow of current when the first tooth upon the wheel 3 comes in contact with spring 11 to cause current to flow to the line wires 1 and 2 as will be hereinafter explained.

When a circuit is completed between a tooth of wheel 3 and the spring 11, current may flow in the following path: positive terminal of battery 20, wires 45, 46, 47, 48, 49, 50, 51, 84, 52, 85 and 66, shaft *s*, first tooth of wheel 3, brush 11, and wires 164, 67, 68, 88, 69, and 70, coil 36 on line relay 34, and wires 71, 72, 58 and 59 to the negative terminal of the source 20. Current flowing in the above traced path causes the right hand end of armature 37, to be raised, thereby causing arm 38 attached thereto to be moved to the left, so causing arms 39 and 40 to be moved to the left and make contact with points 44 and 43 respectively so that current from the generator 22 may flow to line wires 1 and 2 in the following path: positive brush 73, of generator 22, wire 65, point 43, arm 40, and wire 74 to line wire 2, thence along the line wire to the selector station, through all the selectors in multiple to line wire 1, returning to the dispatcher's station A and thence to the generator 22 by means of wire 75, arm 39, point 44, wire 62 and brush 76. It should be noticed that the current flowed out on line wire 2 and returned on line wire 1, and that as there are five teeth upon wheel 3, five positive impulses will be sent to line wire 2 and by the time the last tooth has passed spring 11, the first tooth on wheel 4 will be in position to contact to spring 12, so that current will flow in the following path: positive terminal of battery 20, wires 45, 46, 47, 48, 49, 50, 51, 84, 52 and 77, shaft *s*, tooth of wheel 4, spring 12 and wires 78, 79, 80 and 81, coil 35 on line relay 34 and wires 72, 58 and 59 to the negative terminal of battery 20. Current flowing in the above traced path will cause the left hand end of armature 37 to be raised thereby causing armature 38 to be moved to the right and so cause arms 39 and 40 to contact with wires 41 and

42 respectively, so that current can flow from the generator 22 in the following path: positive brush 73, wire 65, point 41, arm 39, wire 75 to line wire 1 thence along the line 5 wire to the selector stations through the selectors in multiple returning by line wire 2 and thence by means of wire 74, arm 40, point 42 and wire 62 to the negative brush 76. As the wheel 4 has 6 teeth on its periphery, there will be 6 positive impulses sent to line wire 1.

Applicant's system of selectors is such that although any impulse of electricity sent to the line causes all of the selectors at the 15 different stations to operate, the one only which will cause its associated indicator to operate is the one adjusted to be set in a certain definite position by the particular combination of impulses sent to the line. 20 After the wheels 3 and 4 have caused 5 impulses of one polarity and six of an opposite polarity to flow to the line, the selector at station B will be so positioned that another impulse flowing to the line in the 25 same direction as the impulses caused by the make and break by the tooth on wheel 3, will cause the selector to so operate as to cause the indicator associated therewith to operate. This impulse will be obtained by 30 the projection on the wheel 82 contacting with spring 83 so that a circuit is formed in which current flows as follows; positive terminal of battery 20, wires 45, 46, 47, 48, 49, 50, 51, 84, 52, 85, 86, shaft s, projection on 35 wheel 82, spring 83, wires 87, 67, 68, 88, 69 and 70, coil 36 on line relay 34 and wires 71, 72, 58 and 59 to the negative terminal of battery 20. Current in the above traced path causes the right hand end of armature 40 37 to be raised and causes current to flow from generator 22 in the same direction that it flowed when the teeth on wheel 3 made contact with spring 11, that is to say, it flows to line wire 2. The last described impulse 45 is of longer duration than those caused by the teeth on wheels 3 and 4 as the projection upon wheel 82 remains continuously in contact with spring 83 for some time. This last mentioned impulse causes the selector 50 at station B to complete its movement, close a contact and cause an indicator at the station to be operated, in a manner which will hereafter be described.

Wheels 6 and 7, together with sector 8 and 55 wheel 89 operate in exactly the same manner that wheels 3 and 4, sector 5, and wheel 82 operate, the only difference being that wheel 6 has 3 teeth, whereas wheel 3 has 5, and wheel 7 has 4 teeth, whereas wheel 4 has 6. The result of this change is that 3 impulses are sent to the line by operation of wheel 6 and 4 by the operation of wheel 7 and that particular combination of impulses operates selectively upon the selector at station C, so as to place it in such position that

a further impulse, caused by wheel 89 will cause a contact at the selector to be closed and the indicator to be operated.

The selector at the local stations such as B and C, is of a type fully shown, described and claimed in the joint application of Maurice F. Geer and Richard C. Leake, Serial No. 596,252, filed December 8th, 1910, therefore it will suffice in this case to merely point out the general features. 92 and 93 75 designate soft iron cores upon which coils 94 and 95 are wound, the coils being connected together and in multiple with line wires 1 and 2. There is provided a polarized armature 96, oscillatable upon a knife edge 80 pivot 97, there being an arm 98 attached to the armature 96 which carries at its upper end two driving pawls 100 and 101. Driving pawl 100, when moved to the left, contacts with and causes sector 102 to rotate 85 about a central pivot and at the same time causes release pawl 103 to be raised out of engagement with holding pawl 105, thus allowing pawl 103 to drop into engagement, with the teeth 106 of the sector and hold 90 it from rotating backwardly when the driving pawl 100 returns to normal position by reason of spring 141 when the impulse of electricity ceases. Successive impulses advance sector 102 step by step and it 95 is held in its successive positions by holding pawl 105. When the arm 98 is moved to the right, pawl 101 actuates the sector 107 to cause it to rotate about a central pivot and the pawl 108 released from engagement with 100 the tail end 109 of sector 102 by the previous movement of sector 102 falls into engagement with the teeth of sector 107 and holds it in the moved position. The sector 107 has such a number of teeth in its periphery 105 that 18 impulses of such polarity as to move arm 98 to the right, causes the last tooth 110 to engage with the pawl 108 so that although driving pawl 101 may continue to reciprocate, the sector 107 will return after each actuation so that the last tooth 110 rests in contact with holding pawl 108. When the sector 107 has been so moved that holding pawl 108 rests against the last tooth 110, a further impulse will cause the projection 115 111 on sector 107 to engage with spring 112 and force it into contact with spring 113. If 5 impulses are sent through coils 94 and 95 of the selector at station B in such a direction as to cause the right hand end of armature 96 to be drawn upwardly 5 times then the sector 102 will be advanced 5 teeth and as arm 114 is rigidly connected with sector 102, it will be moved to a vertical position, then if sector 107 is advanced 6 120 steps by reason of wheel 4, then arm 115, which is attached thereto, will be moved to a vertical position directly in line with arm 114, then if an impulse is sent to the line by means of wheel 82 and spring 83, the 125 130

right hand end of armature 96 will again be drawn upwardly, the driving pawl 100 moved to the left and by reason of the fact that the tail end 116 of sector 107 has been moved downwardly by the actuation of sector 107, the driving pawl 100 will engage member 117 and rotate it on pivot 118 thereby causing plunger 119 guided by arm 114 to contact with outstanding arm 120 and cause the member 121 to press against spring 122 and cause it to move into contact with spring 123, so that the current flowing along line wire 2 may pass by means of wires 124, 125 and 126 through coil 127 to wire 128, contact 129, armature 130, wire 131, spring 123, spring 122, wires 132, 133 and 134 to line wire 1, and thence return to the generator 22 from whence the current flowing along line wire 2 originated. The current flowing in the above traced path would cause the right hand end of armature 130 to be raised, thereby causing the hammer 135 to strike gong 136 and would at the same time break contact between wire 128 and contact 129 and at the same time make contact between wire 137 and contact 138 so that the current which flowed from wire 125 to wire 126 would then flow through coil 139 to wire 137 and contact 138 to armature 130 and then to wire 131 as before so that the armature 138 would be drawn up on the left causing hammer 135 to strike gong 140 so that a continuous ringing would take place as long as springs 122 and 123 were connected, springs 122 and 123 would be connected as long as the projection on wheel 82 was in contact with spring 83, but as soon as contact was broken at that point the armature 96 would return to its normal position by reason of spring 141, thereby causing arm 98 and pawl 100 to return to the initial position thereby releasing arm 117 which would return it to its initial position and in so doing would cause released pawl 103 to contact with holding pawl 105 and force it from engagement from the teeth of sector 102 thereby allowing sector 102 to return to its normal position, and the tail 109 of sector 102 by contacting with pin 142 would move holding pawl 108 out of contact with the teeth of sector 107 and so allow that sector to return to its normal position so that all parts would return by the mere cessation of current to the normal position.

The selector and bell shown at local station C, Fig. 3, operates in exactly the same manner, the only difference being that in order to ring the bell, the sector 142 must be advanced 3 teeth and the sector 143 must be advanced 4 steps in order that arms 144 and 145 shall be in line.

All of the parts heretofore described have been fully illustrated, described and claimed in the two applications heretofore mentioned, and it now remains to describe the

manner in which applicant is able by the use of the same selective calling apparatus to transmit an announcement of time to each and every local station simultaneously.

Relay 146 is connected to what is called the Western Union time circuit, so that when that circuit is closed, armature 147 is raised. That circuit is closed beginning exactly two minutes before 11 o'clock a. m., and is so arranged that it is closed for an instant only and then immediately opens and is then closed again in one second, and then again opens and so on until exactly fifteen seconds before 11 o'clock, when it is opened and held opened until exactly 11 o'clock, at which time it is closed, thus indicating 11 o'clock exactly. It is then opened and closed every second until two minutes after 11 o'clock so that the despatchers at the central station where this system is installed, should perform the operations hereinafter described some few seconds before two minutes of eleven. The first operations is to move switch 29 so that points 30 and 31 and 32 and 33 are connected. By so doing current is caused to flow in the following path; positive terminal of battery 20, wires 45, 60 and 148, point 32, arm 149, point 33, wire 56, relay 23, wires 57, 58 and 59 to the negative terminal of the battery. The current flowing in the above traced path causes a movement of arm 25 and arm 26, so as to close contact between wires 27 and 28 as heretofore described and cause the motor 21 to operate and cause the armature of generator 22 to rotate. A key similar to the individual keys heretofore described, but having simply wheels 9 and 19 on a common shaft, is then operated and as wheel 9 has but one tooth in its periphery, one impulse will be sent to the selectors at all the different stations to cause the toothed sectors as 102 and 142 to be moved one tooth so that the tail end thereof as 109 may be moved out of engagement with the pins as 142 on holding pawls 108 so that holding pawls 108 may move into engagement with the sectors as 107 and 143. After the single impulse has been sent, wheel 10 then causes 18 impulses to be sent to the line of such a polarity that the sectors such as 107 and 143 at all the stations will be advanced 18 steps so that the holding pawl 108 will rest against the last tooth as 110 and remain in contact therewith.

The first energization of relay 146 causes armature 147 to be raised so that a current then flows in the following path as arm 150 connects points 30 and 31; positive terminal of battery 20, wires 45, 46 and 151, armature 147, wire 152, point 30, bar 150, point 31 and wires 153 and 81, relay coil 35 and wires 72, 58 and 59 to the negative terminal of the battery. Current flowing in the above traced path, causes the left hand end of

armature 37 to be raised and the arm 38 to be moved to the right, thereby causing arms 39 and 40 to contact with points 41 and 42, so that the current flows from the 5 generator 22 in such a direction as to cause armatures as 96 of all of the selectors in the system to have their left hand ends simultaneously raised thereby causing the driving pawls as 101 of all the selectors of the system to move to the right, thereby causing the sectors as 107 to move so that pin 111 will contact with spring 112 and move it in contact with spring 113 at all the stations. When the springs 112 and 113 are connected, 15 current can flow from the line wires in the following path; wires 1, 134, 154, spring 113, spring 112, wire 155, coil 127, wires 126, 125 and 124, to line wire 2. As line wires 1 and 2 are connected to both terminals of the generator 22, the current flowing in the above traced path will cause the right hand end of armature 130 to be raised, thereby striking a single blow on gong 136. As the relay armature 147 is raised and allowed to fall by successive energizations and deenergizations of relay coil 146, the hammer 135 will announce such fact by a single stroke on gong 136. It will be noticed that the bell then operates as a single stroke bell as there is no path for a current flow through coil 139. It must therefore be seen that the blows given the gong 136 correspond exactly with the single clicks of a 30 telegraph instrument, such as is now used for announcing time.

As soon as the last blow has been given the gong 136, the operator at the central station depresses the push button 19, thereby causing current to flow in the following 40 path; positive terminal of battery 20, wires 45, 46, 47, 48, 49 and 156, contact 160, bridging member 19, contact 161 and wires 162, 69 and 70 through the coil 36 on line relay 34 and by wires 71, 72, 58 and 59 to the negative terminal of the battery. The current flowing in the path traced above, causes the right hand end of armature 37 to be raised, the armature 38 to be moved to the left and arms 39 and 40 to be moved in contact with 45 points 44 and 43 respectively, so that current then flows from the positive terminal of generator 22 to line wire 2, and returns by line wire 1, and passes through all of the selectors at the different stations in such a 50 direction that the right hand end of armature 96 is drawn upwardly and as sector 107 is in the moved position and its tail end 116 has been lowered, the driving pawl 100 engages with member 117 and raises the same 55 so that as soon as the movable member 19 is released and the circuit is broken therethrough and the current ceases to flow to the line, the selector becomes deenergized and the arm 117 in returning to normal position by gravity, causes the release pawl 60

103 to engage with the holding pawl 105, throw it out of engagement of the teeth of sector 102, and then allow, as before explained, all of the parts of all of the stations to return to the normal position. 79

Having thus illustrated and described a particular physical embodiment of my invention, what I claim as new and desire to secure by Letters Patent, is:

In a combined time announcing and selective signaling system, in combination: a central station; local stations; two conductors between the central station and the local stations; a source of current at the central station; a motor generator at the central station; a motor control relay at the central station; a line relay at the central station, having an armature and two distinct windings; a plurality of calling keys operable manually, at the central station, 80 each key including a plurality of circuit closers; a plurality of circuits for each key each including one of the circuit closers, one of the circuits including the motor control relay and the source, another including one 85 of the windings of the line relay and the source, and another including the other winding of the line relay and the source; connections from the generator of the motor generator to the two conductors; pole 90 changing contacts inserted in said connections, said pole changing contacts operated by said line relay when one winding is energized to supply one polarity current to 95 said conductors and to supply an opposite 100 polarity current to said conductors when the other winding is energized; a normally open circuit including the motor of said motor generator; a circuit controller for 105 said last named circuit controlled by said motor control relay; a manually operable time key at the central station, said key including a plurality of circuit controllers; a circuit including one of the last named 110 circuit controllers and one of the windings of the line relay and the source; another circuit including another of the windings of the line relay and the source; a manually operable circuit controller; a circuit including 115 said last named circuit controller, the source, and the motor control relay; another manually operable circuit controller; a circuit including said last named circuit controller, the 120 source and one of the windings of the line relay, said circuit further including a circuit breaker operable at definite intervals at a definite time to make and break the circuit; another manually operable circuit controller; a circuit including 125 said last named circuit controller, the source and one of the windings of the line relay; a selector at each of the local stations; a bell at each of the local stations; two circuit controllers; two circuits from one conductor to the other conductor, each 130

of said circuits including said bell, one of the last mentioned circuits including one of the last mentioned circuit controllers, and the other including the other of the last 5 mentioned circuit controllers; said selector operable to close one of said last mentioned circuit controllers upon the operation of one of said calling keys; said selector operable to intermittently close the other of said 10 last mentioned circuit controllers when the

first and second mentioned manually operable circuit controllers are closed and said time key is operated; said third mentioned manually operated circuit controller operable to return the selector to normal position. 15
